UNITED STATES PATENT OFFICE.

ORRIN F. GRIFFIN, OF NEW YORK, N. Y.

ATTACHMENT FOR AUTOMOBILE-ENGINES.

965,626.

Specification of Letters Patent. Patented July 26, 1910.

Application filed April 29, 1908. Serial No. 429,871.

To all whom it may concern:

Be it known that I, ORRIN F. GRIFFIN, a citizen of the United States, and a resident of the city of New York, borough of Manhattan, in the county and State of New York, have invented a new and Improved Attachment for Automobile-Engines, of which the following is a full, clear, and exact description.

10 The invention relates to multi-cylinder engines in which one cylinder of the multi-cylinder engine can be converted into an air pump or compressor adapted to be driven by the remaining cylinders of the engine.

15 The object of the invention is to provide means whereby the valves of the engines may be rendered inoperative.

The invention consists in the construction and combination of parts to be more fully 20 described hereinafter and particularly set forth in the claims.

Reference is to be had to the accompanying drawings forming a part of this specification, in which similar characters of reference indicate corresponding parts in all the views, and in which—

Figure 1 is a side elevation of a two-cylinder internal combustion engine showing my invention applied thereto; Fig. 2 is an enlarged longitudinal section showing a lift rod guide of special construction used in connection with an engine which has my invention applied thereto; Fig. 3 is a side elevation of the lift rod guide showing a part 30 broken away; Fig. 4 is an enlarged longitudinal section of my invention showing the same mounted on the pet cock of an engine cylinder; Fig. 5 is a longitudinal section showing an attachment of modified form; 35 and Fig. 6 is an enlarged end view of a detail of the attachment of modified form.

Before proceeding to a more detailed explanation of my invention, it should be clearly understood that while the same is 45 particularly useful in connection with the engines of automobiles and the like, it can also be advantageously employed with multi-cylinder engines other than those of automobiles.

50 I wish to emphasize the fact that the invention does not reside in the details of construction as shown in the forms of the device illustrated for example, in the accompanying drawings, but that these details of construction can be varied to suit individual preference or special conditions.

The invention resides primarily, in the provision of means for rendering the valves inoperative.

Referring more particularly to the drawings, I have shown, in Fig. 1, a two-cylinder internal combustion engine of the usual form, having cylinders 10, each of which is provided with a valve chest 11 in which are located an inlet valve and an outlet valve. These have valve stems or rods 12 provided with springs 13 which hold the valves normally closed. The valves are mechanically operated by means of lift rods 14 actuated by a cam shaft (not shown). The lift rods 14 move in guides 15 rigidly mounted upon the engine base 16. The lift rods 14 have separate end sections 17 provided with heads 18 adapted to engage at the lower ends of the valve rods and to operate the same as the lift rods are actuated. The lift rod guides have the upper portions 19 which guide the sections 17, movable with respect to the bodies of the guides, and pivoted thereon by means of ears and pivot screws or rivets 21. A locking lever 22 is pivoted upon each of the rod guides and is adapted to engage a bifurcated stop 23 carried by the movable guide section, to lock the parts together. When it is desired 35 to render the valves of the cylinder inoperative it is merely necessary to displace the levers 22 from engagement with the stops 23 and to swing the guide parts 19 with the separate rod section 17 to one side, as is 40 shown in Fig. 1. The valves of the cylinder will then remain closed owing to the action of the springs 13. The lift rod guide sections have, respectively, ribs 20 and grooves 20^a which are adapted to engage to 45 assist in holding the parts in operative position.

Each of the cylinders has a relief pet cock 24 mounted at the top thereof and serving to relieve the compression in the cylinder when the pet cock is open. It has the upper end 25 threaded to receive a correspondingly threaded neck 27 of an elongated member 28. The latter has a longitudinal passage 29 therethrough which communicates at one end with a chamber 30 having a sleeve 31 therein and a spider 32. The chamber is closed by a screw head 33 and communicates with the outer air through a passage 34 of the latter. A ball 35 is arranged in the sleeve 31 and is adapted to close the passage 34 when in position.

at the end thereof and to rest against the spider 32 to permit air to flow through the passage 34 into the passage 29. The latter communicates by means of a passage 36 at 5 substantially right angles thereto, with the passage 37 of the pet cock.

Near the end of the member 28 remote from the head 33 is a second chamber 38 in which is arranged a sleeve 39. The 10 chamber 38 is closed by a head 40 having an elongated discharge outlet 41. A ball 42 is arranged within the sleeve 39 and is adapted to close the passage 29 when the ball rests at the end thereof. When the ball 15 42 is positioned against the head 40, air can escape from the passage 29 through the sleeve 39 to the passage 43, of the head 40, by way of laterally disposed and angularly positioned passages 44 and 45 of the sleeve 20 and the head respectively, these having registering edge grooves 46 with which the passages 44 and 45 communicate. The discharge outlet 41 may be of any suitable form to receive an end of a tube leading to 25 the tires, the fuel tank or other receptacle, and may, as shown, for example in the drawings, be formed to receive a coupling 47 to connect with a flexible tube 48.

When the pet cock 24 is open, communication is effected between the interior of the cylinder and the passages 36 and 29. At the downward stroke of the piston, air is drawn into the cylinder through the passages 34, 29 and 36, the ball 35 assuming a position 35 against the spider 32, while the ball 42 is positioned at the end of the passage 29 to close the same. At the up-stroke of the piston, air is expelled from the cylinder through the passages 36 and 29 and the outlet of the 40 member 28, the ball 35 assuming a position at the end of the passage 34 to close the same, while the ball 42 is positioned against the head 40, leaving the passages 44 and 45 unobstructed. In this way, an efficient single-45 acting pump is formed by the cylinder.

In the modified form of my invention shown in Fig. 5, the head 33 has an enlarged passage 49 therethrough, into which extends a slidable valve member 50 having 50 a head 51 which is adapted to close the passage. The valve member 50 has guide extensions and a stem 52 extending beyond the head and carrying a spring 53 which engages the end of the head and a cross pin 54 of the shank 52 to hold the valve normally closed. The passage 29 adjacent to the chamber 38 is extended to receive a sliding valve member 55 which has a head 56 adapted to close the end of the passage 29.

The head 40, at the inner end, has lateral 60 passages 57 which permit the unobstructed flow of air when the head 56 is positioned against the end of the head 40.

The heads 33 and 40 are preferably buried so that they can be easily screwed into place 65 and removed manually.

The pet cocks may be of any preferred or common form, provided they have the upper portions threaded, suitably to receive 70 the members 28.

The device may be fashioned from any suitable material such as cast metal or the like.

Having thus described my invention, I claim as new and desire to secure by Letters 75 Patent:—

1. In an engine, the combination with the cylinder, its valves, and valve stems, of lift rods for operating the valves, each rod being formed of disconnected sections, and 80 means whereby one section of each rod may be moved out of alignment with the other section and the valve stem to render the valve inoperative.

2. In an engine, the combination with the 85 cylinder, its valves, and valve stems, of guides formed of sections movable relatively one to the other, and lift rods movable in the guides and formed of disconnected sections, one in each section of a guide. 90

3. In a multi-cylinder engine, the combination with the cylinders and their valves and valve stems, of guides in alignment with the valve stems and each formed of two sections hinged together, means for locking the 95 sections of the guides together, and sliding lift rods for the valve stems, each rod being formed of two sections, one in each of the sections of the guides.

4. In a multi-cylinder engine, the combination with the cylinders, and their valves and valve stems, of guides below the valve stems and each formed of two sections hinged together, a bifurcated stop on the 105 hinged section of each guide, a lever pivoted to the fixed section of each guide and adapted to engage the said stop, and sliding lift rods in the guides for operating the valve stems, each lift rod being formed of two sections, one in each section of the guide, the 110 upper section being provided with a head.

In testimony whereof I have signed my name to this specification in the presence of two subscribing witnesses.

ORRIN F. GRIFFIN.
